INVENTOR
Alexander P. Schaap
BY
O. Avery Edwards
ATTORNEY

UNITED STATES PATENT OFFICE.

ALEXANDER K. SCHAAP, OF BROOKLYN, NEW YORK.

APPARATUS FOR MAKING PISTON-RINGS.

1,325,659.

Specification of Letters Patent. Patented Dec. 23, 1919.

Application filed March 18, 1918. Serial No. 222,992.

To all whom it may concern:

Be it known that I, ALEXANDER K. SCHAAP, a citizen of the United States, and a resident of the city of New York, borough 5 of Brooklyn, county of Kings, and State of New York, (whose post-office address is 344 Cumberland street, in said city,) have invented a new and useful Improvement in Apparatus for Making Piston-Rings and 10 Also in the Method of Making the Same, of which the following is a specification.

The principal object of my invention is to provide a piston ring which will at all times fit true and wear true and without binding 15 in the position in which it is placed, and give a maximum of efficiency while in use. This object is accomplished by the product of my invention which will now be more particularly set forth.

20 For a more particular description of my invention, reference is to be had to the accompanying drawings, forming a part hereof, in which.

Figure 1 is a plan view of a portion of a 25 machine embodying my invention with the first cut being taken.

Fig. 2 is a plan view of a portion of a piston ring showing the condition of the ring after the first cut.

30 Fig. 3 is a plan view of the apparatus when making the second cut.

Fig. 4 is a corresponding view of a portion of the ring just after the second cut has been taken.

35 Fig. 5 shows the apparatus and ring while the third cut is being taken, after the ring has been turned over.

Fig. 6 shows the condition of the ring at the finish of the cut.

40 Fig. 7 shows the apparatus taking the fourth cut.

Fig. 8 shows the condition of the ring when this cut has been completed.

Fig. 9 is a sectional view, taken on the 45 line 9—9, of Fig. 5, looking in the direction of the arrows.

Fig. 10 is a plan view of the apparatus when ready to take the third cut, parts being removed to more clearly reveal the 50 structure.

Fig. 11 is a sectional view, taken on the line 11—11 of Fig. 5, looking in the direction of the arrows.

55 Figs. 12 and 13 show the compressing jacket used when putting the rings on a

mandrel after they have been cut, as shown in the preceding figures, Fig. 12 being a sectional view, taken substantially on the line 12—12 of Fig. 13, looking in the direction of the arrows. 60

Figs. 14 and 15 show a group of rings on a mandrel ready for grinding.

Throughout the various views of the drawings, similar reference characters designate similar parts. 65

It is not necessary to go into the preliminary stages of the manufacture of a packing ring, because they may be of any suitable kind and form no part of this invention. It is sufficient to say that the rings embodying 70 my invention may be made from any suitable blanks, as a casing of the conventional form which is first placed in a suitable grinding machine and ground so as to have its flat faces made absolutely true and in 75 parallel planes. Assuming the rings to be in this condition they are then placed on a suitable mandrel and turned and ground until they are a little too large, say about one hundred and fifty thousandths of an 80 inch too large, depending upon the nature of the ring and the amount of finishing cut desired. Assuming the blanks to have been thus prepared they are then ready for my improved apparatus and methods, and are 85 treated as will now be described.

The blank 1 is put in a chuck 2 of the milling machine 3 and clamped firmly by means of a suitable clamp 4. This machine 3 has a milling cutter 5, which is in 90 the nature of a saw, about $\frac{1}{16}$ of an inch thick, and of any suitable diameter, say $2\frac{1}{2}$ or 3 inches, and is mounted on a spindle 6, which is driven in the conventional way by any suitable means, not shown. This 95 spindle 6 has its cutter 5 so placed with regard to the chuck 2 that this chuck may turn on a pivot 7 with its axis resting in the median plane of the cutter 5 and intersecting the axis of the spindle 6 when in its mid-position. If this position of the pivot 7 is not obtained the rings 1 will be defective and the defect will be serious and defeat the purpose of this invention when this pivot 7 is substantially out of its true position. 100 105

The pivot 7 extends into a table 8, which has a reciprocating movement of the conventional kind, as is customary in milling machines. The table 8 reciprocates in the 110

general direction of the median plane of the cutter 5.

The clamp 4 may be made in any suitable way, and in the preferred embodiment of 5 my invention, consists of a suitable bolt 9 which is screw-threaded into the table 8 and passes upwardly through the chuck 2. This bolt is provided with a suitable bar 10 which extends over the ring 1 (see Fig. 9) and 10 under a suitable cap-screw 11 where it may be secured with a free turning movement at one side and clear of the chuck 2.

The chuck 2 rests flat on the bed 8 and turns on its pivot 7 and is provided with a 15 circular opening 12 at its center, so that it will swing until limited by a washer 9^a on the bolt 9, and the chuck 2 is also provided with a suitable collar 13 against which the ring 1 may rest under normal conditions 20 and be securely held while being cut, as well as a handle 14 which is secured to it by any suitable means, as screws, which are preferably placed so that the handle 14 is diametrically opposite the pivot 7, and there is 25 also mounted on this chuck a segmental plate 15 (see Fig. 10) which carries a suitable tongue 16 and this plate is locked in position by means of a set screw 17. The tongue 16 is so placed and shaped that it 30 will lie in the cut of the ring 1 shown in Fig. 4, and fit snug within the same so as to support this ring in its true position and hold it true while it is receiving the third and fourth cuts.

35 The diameter of the hole 12 is such, when taken in connection with its position, that the handle 14 may be swung to the right of the vertical plane containing the axis of the spindle 6 to substantially 7 degrees, as 40 shown in Fig. 1. The cut when so taken may be designated by the character 18. After this cut 18 has been so made, a second cut is made after the handle 14 has been thrown to the left a like amount. The second cut engages the cut 18, as shown in Fig. 4, until it becomes what might be designated the cut 19 when the converging walls 20 and 21 are not parallel as are the walls of the cut 18. The foregoing description has been 45 given for a ring substantially 4½ inches in external diameter. The walls 20 and 21 are not quite in their ideal locations because of the thickness of the cutting tool 5. The ideal position would be the median plane of 50 the cutting tool 5. This is not practical because the cutting tool must necessarily have sufficient thickness to make it strong enough to perform its functions. However, as the respective edges 20 and 21 are cut parallel 55 with their respective ideal positions and equidistant therefrom, they sufficiently approach the ideal positions to enable them to perform their functions properly. After the cut 19 is made the ring 1 is removed 60 from the chuck 2 and then the part 15 is 65

inserted, as shown in Fig. 10, with its tongue 16 adapted to enter and fit snug in the groove 19, when the ring 1 is again placed in the chuck 2. While the ring 1 is out of the chuck 2, a new washer 9^a is substituted 70 which is substantially thirty thousandths of an inch larger.

The clamp 4 is released so as to enable the ring 1 to be either removed or shifted, and it is always tightened after the shifting or 75 removal has taken place and the chuck and ring are in their proper respective positions. When the ring 1 is in the positions necessary for the third cut it is taken, as shown in Fig. 5, with the handle 14 at the left instead of the right, and then the cut 22 appears, as shown in Fig. 6. After this cut has been made the clamp 4 is released, the chuck shifted about 11 degrees and 27 minutes, because of the enlarged washer 9^a, to 80 the position shown in Fig. 7, when the clamp is again secured and then the finishing cut is made, as shown in Fig. 8, where the groove 23 appears and it is provided with the converging walls 24 and 25. These 85 walls correspond to the walls 20 and 21 of the groove 19. Thereafter the ring may be removed from the chuck 2 and placed with a number of other rings, as shown in Figs. 12 and 13, in the jacket 26, which is then 90 tightened by means of the bolts 27, until the joints of the rings are closed tight. These rings are then placed on a mandrel 28, in the conventional manner, as shown in 95 Figs. 14 and 15, and ground to their correct diameters, after which they are finished and may be removed from the mandrel and used. When in use the edges 20 and 21 engage each other and so do the edges 24 and 25 and they engage so as to form a gas-tight joint. The depth of the cut 18 and the succeeding cuts is such that they extend 100 only half way through the ring 1 so that when all the cuts are completed and the ends of each ring are brought together there 105 is a snug fit of the parts which rub on each side median plane of the ring. From this it is apparent that the three engaging surfaces at each end of each ring engage with a sliding fit, which is true, or nearly so, for 110 each position of the ring so that under all conditions of service these ends engage with a gas-tight fit, which will prevent all leakage, and yet the ring is free to slide in a cylinder of irregular or varying diameter 115 without losing the tight fit or binding or breaking.

Having thus described my invention, what I claim is:

1. In a machine of the class described, 125 means for holding a blank ring so that a diagonal cut may be taken, means for shifting the ring after the first cut through an angle about a center under the axis of the cutter, and at or near the periphery of the 130

ring and means for taking the first and second cuts.

2. In a machine of the class described, a rotary cutter, a table carrying a chuck which is adapted to be swung on an axis passing through the median plane of the cutter and at or near the periphery of the ring, and means for clamping a piston ring so that a cut may be taken when it is held in either

10 of two positions of said chuck.

3. In a machine of the class described, a cutter having a median plane, a table having a feed in the direction of said plane, a pivotally mounted chuck adapted to be

15 clamped in two positions with a pivot pass-

ing through said median plane and through the periphery of the ring being cut.

4. In a machine of the class described, a cutter having a median plane, a table adapted to be shifted in the direction of said plane, a chuck pivotally mounted on said table with the axis of its pivot in said median plane and also in the periphery of a ring which is held by said chuck and cut by said cutter, a clamp adapted to hold said ring in said chuck, a tongue adapted to fit in said ring and give said ring a correct position with regard to said cutter and means for holding said tongue in place.

ALEXANDER K. SCHAAP.
